DESIGN FOR A CASE FOR MICROMETER CALIPER

William B. Hunter, Wellesley Hills, Mass., assignor
to The Comtor Company, Waltham, Mass., a
corporation of Massachusetts

Application June 24, 1944, Serial No. 114,189

Term of patent 14 years

(Cl. D52—2)

To all whom it may concern:

Be it known, that I, William B. Hunter, a citizen of the United States, residing at Wellesley Hills, in the county of Norfolk and State of Massachusetts, have invented a new, original, and ornamental Design for a Case for Micrometer Caliper, of which the following is a specification, reference being had to the accompanying drawing, forming a part thereof.

Fig. 1 is a perspective view of the case for micrometer caliper showing my new design, Fig. 2 is a front view of the same, and Fig. 3 is a side elevation looking from the left of Fig. 2.

I claim:

The ornamental design for a case for micrometer caliper, as shown.

WILLIAM B. HUNTER.
